(57) **CLAIM**

The ornamental design for a light therapy eye patch, as shown and described.

DESCRIPTION

FIG. 1 illustrates a front perspective view of light therapy eye patch;

FIG. 2 illustrates a front view of light therapy eye patch thereof;

FIG. 3 illustrates a back view of light therapy eye patch thereof;

FIG. 4 illustrates a left side view of light therapy eye patch thereof;

FIG. 5 illustrates a right side view of light therapy eye patch thereof;

FIG. 6 illustrates a top view of light therapy eye patch thereof;

FIG. 7 illustrates a bottom view of light therapy eye patch thereof;

FIG. 8 illustrates a environmental view of light therapy eye patch thereof; and,

FIG. 9 illustrates an in-use view of light therapy eye patch thereof.

The broken lines shown in the drawings are included for illustration purpose only and form no part of the claimed design.

1 Claim, 8 Drawing Sheets
